(57) **CLAIM**

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

This application which is related to U.S. Design application Ser. No. 29/658,973 and U.S. Design application Ser. No. 29/658,972 the disclosures of which are herein incorporated by reference.

The FIGURE is a front view of a portion of a display screen showing my new design for a display screen or portion thereof with graphical user interface.

The dashed broken lines that form a round-cornered rectangular border are included in the claimed design.

The wavy outer dot-dot-dash rectangle illustrates the perimeter of a portion of a display screen. The wavy outer dot-dot-dash rectangle forms no part of the claimed design.
